LIGHTING FIXTURE

Theodore Chanock, Chicago, and Erwin Freyer,
Oak Park, Ill.

Application March 18, 1933. Serial No. 661,556

2 Claims. (Cl. 240—81)

The present invention relates to lighting fixtures, and more particularly to a fixture of the "indirect" type in which an inverted bowl-shaped reflector is employed to throw light rays upwardly from the fixture.

The principal objects of this invention reside in providing a protecting cover for the inverted reflector in order to avoid accumulations of dust and foreign matter within the same which have 10 a tendency to dim the same and reduce its efficiency; to provide a circulation of air through the thus closed reflector in order to ventilate the same and prevent overheating; to provide a simple mode of mounting a decorative shade upon the fixture which allows said shade to be readily removed whenever desired; and to fabricate and assemble the before-mentioned elements in a manner that will permit such parts as the cover, the shade, the shade-mounting bracket and the 15 reflector to be readily dismantled for renovation or replacement.

Further objects are to provide a device of the character disclosed that is novel in construction, easy to manipulate, dependable in operation, and 20 economical to manufacture.

All of the numerous objects and advantages of this invention are accomplished by means of the structure described in the following description, and more particularly pointed out in the appended 25 claims.

Reference is made to the accompanying drawing that forms a part of this specification, in which:—

Figure 1 is a side elevation of this invention, 30 with portions broken away and in vertical section to disclose the interior constructions.

Figure 2 is a top plan of the shade mounting bracket seated on the reflector, drawn to a larger scale than Figure 1, and,

Figure 3 is a top plan of a fragment of the ring or annular band of said bracket removed from the reflector.

Figure 4 is an enlarged detail in vertical section showing portions of the reflector, cover and shade 40 mounting structure in assembly.

Figure 5 is an enlarged detail in vertical section showing the lower portion or neck of the reflector.

The drawing is to be understood as being 50 more or less schematic, and is for the purpose of disclosing a typical or preferred form in which the improved fixture may be made, it being understood, of course, that modifications of the precise structures disclosed may be made without 55 departure from the principles involved.

The structure shown in Figure 1 comprises a support in the form of a standard 10, arising from a wide base, and having radial arms 11 at its upper portion that have upturned extensions in which suitable electric sockets (not shown) 60 are disposed to receive a plurality of lamps or bulbs 12. The electric current to the sockets and bulbs is controlled by a button switch 13 on a convenient portion of the fixture.

Above the junction of the arms with the standard the latter is provided with a cup-shaped metal husk 14 that surrounds a centrally disposed electric socket (not shown) to receive a large lamp or bulb 15 that extends up above the horizontal plane of the small bulbs 12 and the lighting of 70 which is controlled by a pull-chain switch designated by the numeral 16.

The upper portion of husk 14 is threaded to be engaged with threads at the lower end of the reduced neck portion 17 of the reflector 18. The 75 body of the reflector is bowl-shaped, being flared outwardly and upwardly from the neck and surrounds the lamp or bulb 15 so that light rays received by the inner surface of the bowl are reflected up towards the ceiling.

Around the upper edge of the reflector 18 there is a rim 19, of substantially L-shape cross section, that provides an annular seat for positioning a cover 20 across the top of the reflector. This cover is of light-transmitting material, preferably 85 glass and it is of an inverted dish-shape having a concave-convex cross section. As shown, the outer surface of the cover is smooth while the inner surface is stippled or roughened in order to break up the light rays that pass upwardly through the cover from the bulb and reflector. This cover 20 prevents dust and foreign matter from falling into the reflector and thus 90 reducing its efficiency.

On account of closing the top of the reflector it will be obvious the interior thereof will become heated from the temperature radiated by the bulb. To overcome this suitable vent openings 21 are provided in the upper portions of the reflector below the seat 19, and in the lower portion of the neck other vent openings 22 are provided which are formed by making an inverted U-shape cut or slit in the neck of the reflector so that the intermediate portion of the metal between the parallel arms of each slit may be 100 bent inwardly to provide vanes 23. This permits air to enter at the lower portion of the neck but prevents light rays from passing outwardly.

The fixture thus described is provided preferably with a shade 24 of any suitable or ornamental

mental design that is of sufficient height to extend down below the horizontal plane of the auxiliary lamps 12 and up above the horizontal plane at the top of the reflector 18 and its dome-shaped cover.

5 The shade is open at its top and is made with the usual wire or metal frame which has radiating arms 25 extending inwardly from its upper edge. In order to mount the shade in the manner shown an annulus or circular band 26 is provided which is slightly larger in diameter than the upper edge of reflector 18, and it is provided with a spider-bracket consisting of radiating arms 27 that bow upwardly and arch over the dome-cover of the reflector in the manner shown in Figure 1.

10 The lower end portions of these arms are bent laterally into horizontal planes to provide feet 28 that rest upon the upper edge of the reflector body and extend across the top surface of the circumferential edge of the cover 20 as shown in Figure 4 to maintain the cover in its seat. The upper inner ends of the arms 27 are connected to a boss 29 above the cover, which is in alignment with the axis of the reflector. The 15 inner ends of the arms 25 of the shade are connected to a central boss 30 which is connected to the boss 29 of the bracket by a screw co-operating with the ornamental tip 31.

15 The annular band 26 is of such width, or vertical height, that its lower edge is below the horizontal plane of the vent openings 21 in the reflector so that light rays from the interior of the reflector which may pass through said openings will strike against this depending apron and will not be transmitted to the shade where such light rays might mar the artistic effect of the shade.

20 In order that the mounting bracket may be readily attached to or moved from the reflector a friction device in the form of a spring tongue 32 is provided upon the inner surface of the annulus or band 26 and when not in use, as shown in Figure 3, this tongue projects spirally

into the ring, but when the bracket is mounted upon the reflector this tongue will frictionally engage the adjacent edge of the reflector and removably maintain the bracket in position.

10 It will readily be seen that the shade, with its spider bracket may be removed bodily from the reflector by raising the aforesaid structure upwardly to release it from the reflector. It will also be seen that the shade is illuminated solely from the auxiliary bulbs 12, and that the indirect light will be reflected by the reflector upwardly through the translucent cover 20 and directed to the ceiling or other plane surface above the fixture, while the reflector is protected from dust and foreign matter and is effectively ventilated.

15 What we claim is:—

1. An illuminating device comprising an inverted bowl-shaped reflector for directing light rays upward, a light transmitting cover closing the top of said reflector, said reflector having vent openings below said cover, a shade surrounding said reflector, and means for mounting said shade consisting of radially disposed arms arched upward from said reflector and having portions that engage said cover, and an annular band connecting the lower ends of said arms and extending below said vent openings.

2. An illuminating device comprising an inverted bowl-shaped reflector for directing light rays upward, an annular seat adjacent the top of said reflector, said reflector provided with vent openings below said seat, a light transmitting cover disposed in said seat to close the top of said reflector, a shade surrounding said reflector, and means for mounting said shade consisting of radially disposed arms arched upward from said reflector and having portions that engage said cover, and an annular band connecting the lower ends of said arms and extending below said vent openings.
